H. ORSENIGO.
PHONOGRAPH.
APPLICATION FILED SEPT. 29, 1920.

1,414,151.

Patented Apr. 25, 1922.

UNITED STATES PATENT OFFICE.

HENRY ORSENIGO, OF MOUNT VERNON, NEW YORK.

PHONOGRAPH.

1,414,151.

Specification of Letters Patent. Patented Apr. 25, 1922.

Application filed September 29, 1920. Serial No. 413,507.

To all whom it may concern:

Be it known that I, HENRY ORSENIGO, a citizen of the United States, residing at Mount Vernon, Westchester County, State 5 of New York, have invented certain new and useful Improvements in Phonographs, of which the following is a specification.

This invention relates to phonographs.

An object of the invention is to provide a 10 phonograph with movable panel or closure member for the discharge opening of the phonograph and open to view for the purpose of enhancing the phonograph as an article of furniture when not in use as a phonograph and to provide means for 15 mounting such panel or closure member to conceal such panel when removed. Such provision of means affords a suitable arrangement whereby the motor of the phonograph is placed in operative connection automatically upon concealing such panel in its opening position and automatically effecting non-operative relation of the motor and the phonograph parts when the panel 20 or closure member is in its viewed position.

In carrying out my invention in the most preferred forms, I have provided for phonographs having a driving motor for driving the shaft of the turn-table, a panel for concealing the grill-work or other terminal 30 decoration of the horn or discharge opening of the phonograph and open pivotal means for removably mounting the panel whereby upon concealing the panel the switch connecting the electric supply conductors with 35 the motor circuit is moved to closed position preparatory for operating the motor for rotating the turn-table.

Such panel is preferably mounted on a 40 pivot hinge. The panel is usually decorated in symmetry with the fixed panels or other decorated parts of the phonograph.

Further features and objects of the invention will be more fully understood from the 45 following description and the accompanying drawings, in which Fig. 1 is a perspective view of a phonograph embodying my invention, showing the panel in position when the phonograph is not in operation; Fig. 2 50 is a similar perspective view partially broken away to show hidden parts and showing the panel moved to its concealed position and the contact member of the motor circuit closed, in which relation the grill-work 55 of the phonograph is shown to view;

Fig. 3 is a detail sectional view on line

3—3 of Fig. 2; Fig. 4 is a detail sectional view on line 4—4 of Fig. 3; Fig. 5 is a detail perspective view of the panel; Fig. 6 is a detail perspective view similar to Fig. 3, showing a modification; and Fig. 7 shows a further modification.

The cabinet of the particular phonograph shown in Fig. 1 is of period design but such form and construction may be modified as 60 may be desired. In the particular design illustrated, the panel 1 is employed to conceal the grill-work 2, see Fig. 2, and other ornamentation at the terminal portion of the horn or discharge opening 3 of the 65 phonograph. For the purpose of ornamentation the outer face of panel 1 conforms to the symmetrically arranged panels 4, 5, 6, etc., of the phonograph whereby the phonograph is enhanced in value as an ornamental article, when not in use as a phonograph.

In the form shown in Figs. 1 and 2, the panel 1 is hinged at its lower end by the provision of the oppositely disposed pivots 7, 7, coacting with the oppositely disposed 70 grooves 8, 8, in the respective blocks 9, 10. As will be noted from Figs. 2 and 4, the block 9 serves as the right-hand side of the discharge opening 3, partitioning the phonograph section or compartment 11 from the 75 right-hand section or compartment corresponding to the panel designated 5. Other suitable types of open pivot hinge means may be employed.

The block 10, as appears from Figs. 2 and 90 4, is in the form of a strip and is secured to the left-hand side 12, partitioning the section or compartment 11 from its left-hand section or compartment corresponding to the panel 4.

If desired, the panel 1 may be provided with the knob 13 whereby the panel may be grasped and swung outwardly and downwardly to approximately horizontal position, whereafter the panel 1 is pushed inwardly to conceal the panel 1, at the bottom of the interior of the phonograph section or compartment 11. Preferably the weight of the panel 1 is borne independently of the pivots 7 in the respective grooves 8 as by 100 means of the strips 14, 15, secured to the base board 16 and having layers of felt 17, 18, on their faces which are engaged by the panel 1.

Any approved type of electrical contact 110 member or device 20 may be employed; in the particular contact device 20, shown dia-

grammatically, the conductors 21, 22, lead from the source of power and the conductors 23, 24 lead to the motor circuit of the phonograph. The movable switch element 25 is mounted to be pushed inwardly substantially horizontally to bridge the contacts 26, 27. The movable switch element 25 is provided with the spring 28 for releasing the movable switch element 25 outwardly and 10 open the motor circuit.

Associated with the movable switch element 25, I have arranged the trip member 30 having the upstanding end portion 31 for engaging the free end of the movable 15 switch element 25 and having the downwardly extending end portion 32 adapted to be engaged by the rearward or downward edge 33 of the panel 1, when the panel 1 has been pushed sufficiently within the compartment 11.

The block 34 is provided for limiting the maximum inward movement of the panel 1. The trip element 30 may be suitably mounted on the pivot pin 35, secured to the 25 standard 36 and attached to the block 10. Upon pushing the panel 1 fully to its inward or concealed position, the weight of the panel and its frictional engagement with the strips of felt 17, 18, is sufficient to hold 30 the movable switch element 25 in circuit closing position.

When the panel 1 is withdrawn from its concealed position, the spring 28 causes the movable switch element 25 to be moved outwardly thereby placing the contact member 20 in open circuit position, the panel 1 being pulled outwardly until its pivot has reached the outer terminals of the grooves 8, 8, and thereafter permitting the panel 40 1 to be swung outwardly and upwardly to its closing position, as shown in Fig. 1, in which position the grill-work 2 and other ornamentation of the discharge opening 3 is concealed.

45 The panel 1 is shown in Fig. 1 in its closed position and in Fig. 2 in its open or concealed position. In Fig. 3, the full line outline of panel 1 shows the panel 1 partially concealed, whereas its closed position 50 is indicated in dotted outline.

In Fig. 6 I have shown a modification, in which the panel 1 slides within the section or compartment 40 which is separate from the phonograph section or compartment 41, the arm 32 of the tripping member 30 extending through the slot 42 in the bottom 43 of the compartment 41, the remaining parts of the arrangement corresponding similarly to the aforesaid parts and bearing 60 like reference numbers.

My invention is also applicable for use with a spring wound or other motor, by providing a suitable spring-pressed lever 50 for braking the turn-table 51, and an actuating lever 52 controlling the brake lever 65

50, such actuating lever 52 coacting with the rear edge 33 of the panel 1, whereby as similar to the coaction of the panel 1 and the electric switch lever 33 in the arrangements hereinabove shown, the braking lever 70 50 is forced by the panel against the action of the spring 53 into non-braking position when the panel 1 is moved to its concealed position and thereby permitting the turn-table 51 to be rotated; and upon moving 75 the panel 1 to its viewed position, the braking lever 50 is moved and held by the spring 53 in braking relation with the turn table 51.

Usually the cabinet is supported on appropriate legs 45, and otherwise arranged or 80 ornamented as may be desired.

Whereas I have described my invention with reference to specific forms thereof, it will be understood that many changes and modifications may be made without departing 85 from the spirit of the invention, as defined by the appended claims.

I claim.

1. In combination with a phonograph having a turn-table, motive means therefor, 90 and a sound discharge opening, of a member, means for mounting said member when in one position to effectively close said sound discharge opening and for supporting said member when moved from its closing position to another position, and means operated by said member when moved to its said another position for rendering said motive means effectual relative to said turn-table and when said member is moved to its said 100 one position for rendering said motive means ineffectual relative to said turn-table.

2. In combination with a phonograph having a turn-table, motive means therefor, and a sound discharge opening, of a member, means for mounting said member when in one position to effectively close said sound discharge opening and for concealing supporting said member when moved from its closing position to another position, and means operated by said member when moved to its said another position for rendering said motive means effectual relative to said turn-table and when said member is moved to its said 110 one position for rendering said motive means ineffectual relative to said turn-table.

3. In combination with a phonograph having a turn-table, motive means therefor and a sound discharge opening, a panel, hinge mounting means for said panel to effectively close said sound discharge opening when swung in one position, a housing for receiving and supporting said panel when moved from its closed position to its non-closing position and means operated by said panel upon being moved into said housing for rendering said motive means effectual relative to said turn-table and when said panel is moved to its said one position for 120 125 130

rendering said motive means ineffectual when said panel is in its concealed position relative to said turn-table.

4. A phonograph comprising a cabinet, a sound reproducing means disposed in said cabinet, said reproducing means including a motor; said cabinet being provided with a sound discharging opening, a panel for closing said sound discharging opening, slotted means for pivoting said panel and means for substantially concealing said panel, constructed and arranged whereby when said panel is in its concealed position the motor is in operative relation with the sound reproducing parts of the phonograph and when the panel is in its viewed position closing the sound discharging opening the motor is in inoperative relation with the sound reproducing parts.

In testimony whereof I have signed this specification this 27th day of September, 1920.

HENRY ORSENIGO.
